US00D615958S

(12) **United States Design Patent**
Tkachuk et al.

(10) **Patent No.:** **US D615,958 S**
(45) **Date of Patent:** **** May 18, 2010**

(54) **COMBINED WIRELESS INTERNET PHONE
AND CHARGER**

(75) Inventors: **Steven Tkachuk**, Los Angeles, CA (US); **Tae-Hun Kim**, Seoul (KR); **Kyung-Hoon Lee**, Seoul (KR); **Sang-Sung Woo**, Seoul (KR); **Tai-Hyung Ju**, Seoul (KR)

(73) Assignee: **Samsung Electronics Co., Ltd.**, Suwon (KR)

(**) Term: **14 Years**

(21) Appl. No.: **29/343,018**

(22) Filed: **Sep. 4, 2009**

(30) **Foreign Application Priority Data**

Jun. 3, 2009 (KR) 30-2009-0024423

(51) **LOC (9) Cl.** **14-03**

(52) **U.S. Cl.** **D14/148**

(58) **Field of Classification Search** ..... D14/137, D14/138 R, 138 AA, 138 AB, 138 AD, 138 C, D14/138 G, 143-144, 147-148, 156, 218, D14/247-248, 341-347, 390, 399, 455-456, D14/496, 138 AC, 224, 149-150; D13/164, D13/168, 108; 320/108; D21/329, 331, D21/333, 517; 348/14.01-14.02; 361/814; 379/433.01-433.13, 428.01-428.02, 434, 379/451-452; 455/90.3, 556.1-556.2, 566, 455/575.1, 575.3, 575.4
